UNITED STATES PATENT OFFICE.

JAKOB CASPAR WALIGURSKY, OF PALATKA, MICHIGAN.

WRENCH.

1,158,343.

Specification of Letters Patent.

Patented Oct. 26, 1915.

Application filed June 22, 1915. Serial No. 35,542.

To all whom it may concern:

Be it known that I, JAKOB CASPAR WALIGURSKY, a subject of the King of Hungary, residing at Palatka, in the county of Iron 5 and State of Michigan, have invented certain new and useful Improvements in Wrenches, of which the following is a specification.

This invention relates to new and useful 10 improvements in wrenches.

The primary object of this invention is the provision of a quick action wrench having one of its jaws provided with a resiliently mounted pivoted serrated face adapted 15 for engaging the work and which co-operates with an oppositely positioned jaw face whereby an initial gripping of the work positioned therebetween is insured.

A further object is to provide a wrench 20 having a uniform exterior surface and with solid jaw faces at one side thereof and combined interchangeable and resiliently pivoted faces at its opposite side whereby the wrench is adapted for use either as a pipe wrench 25 or an ordinary nut wrench.

With these general objects in view and others that will appear as the nature of the invention is better understood, the same consists in the novel combination and arrangement of parts hereinafter fully described, 30 illustrated in the accompanying drawings and pointed out in the appended claim.

In the drawings forming a part of this application and in which like designating 35 characters refer to corresponding parts throughout the several views, Figure 1 is a side elevation of the wrench, portions of the same being broken away. Fig. 2 is a front elevation thereof partially broken 40 away along the central longitudinal axis of the handle. Fig. 3 is a top plan view of the device. Fig. 4 is a transverse sectional view taken upon line IV—IV of Fig. 1. Fig. 5 is a transverse sectional view taken upon 45 line V—V of Fig. 1, and Fig. 6 is a perspective view of the jaw plate receiving portion of the wrench body with the plate removed.

Referring more in detail to the drawings, 50 the wrench body 10 is illustrated as provided with an operating handle 11, while the said body is provided with a central longitudinal bore substantially rectangular in cross section and terminating at the end face 13 of the said wrench body while the

other end of the bore communicates with an open T-shaped slot 14 formed transversely through the said body.

A head 15 is provided with a projecting shank 16 which terminates in a threaded shaft 17 and the said shaft is slidably inserted within the bore 12 and with the threaded shaft extending within the slot 14, while a turn nut 18 is threaded upon the shaft 17 and is located within the transverse portion 19 of the said T-shaped slot 14.

From this construction it will be evident that upon a turning of the adjusting nut 18 the shaft 17 and shank 16 will be moved either inwardly or outwardly of the wrench body, thus communicating a corresponding movement to the head 15, relatively of the body face 13.

The head 15 is provided at one end with the rigid jaw 20 lying opposite to the face 13 of the wrench body and co-operating therewith for engaging the work when the said head is moved under the influence of the said adjusting nut 18. A removable jaw 21 is secured by means of a removable pin 22 to the head 15 at a point opposite to the rigid jaw 20 of the said head, while such jaw 21 is provided with a serrated inner face 23 lying opposite to a portion of the end face 13 of the jaw body which is provided 25 with an angularly stepped or cut away portion or recess 26. The recess 26 has its inner portion provided with a curved side 27 and its outer portion provided with an offset slanting side or bottom 28, the latter terminating in the straight outer wall 29 of the wrench body. A substantially wedge-shaped lug 30 is mounted upon the said body wall 29 and has its outer face 31 formed arcuate concentric with the pivotal opening 32 transversely arranged through the said lug while the adjacent portion of the lug extends above the recess bottom 28 as at 33 and substantially to the level of the adjacent edge 34 of the curved side 27 of the recess. A jaw plate 35 is provided having spaced lugs 36 and adapted for the reception of the lug 30 therebetween, a pivot pin 37 being provided through the perforation 32 and also through the lugs of the jaw plate. It will be noted 35 that the jaw plate 35 is formed upon one side thereof conforming in shape to the configuration of the aforementioned recess while curved leaf springs 38 are secured to the recess bottom 28 and against which the jaw 40

100

105

110

plate resiliently seats. The opposite side of the jaw plate is serrated as at 39 and is co-operatively positioned opposite the jaw face 23.

5 The plate 35 is provided with a socket 40 between the plate lugs 36 and conforming to the shape of the lug 30 while the said plate is adapted to be swung upon the pivot pin 37 in an arcuate path and to the position 10 illustrated in dotted lines in Fig. 1 for purposes of cleaning the faces of the underlying recess.

15 It will thus be seen that the action of the springs 38 upon the jaw plate is to allow a pressure upon the plate face 39 by the work to intially compress the springs 38 as well as to depress the plate 35 and thus afford an initial gripping of the work between the serrated faces of the two jaw members 21 20 and 35.

25 The complete operation of the device will be apparent from the above detailed description thereof, it being noted that in moving the head 15 relative to the body 10 by means of the turn nut 18, the distance between the serrated faces is made substantially the same as the thickness of the work to be engaged by such faces and when the serrated faces are moved into engagement with the work 30 the jaw plate 35 is depressed while engaging the same thereby insuring a gripping of cylindrical surfaces such as pipes and bars. The turn nut 18 is further employed for more firmly seating the jaw faces against

the work as well as for designating faces 35 therefrom.

What I claim as new is:—

A wrench comprising a body portion having a fixed jaw at one side thereof, a movable jaw coöperating with said fixed jaw, 40 said fixed jaw having a stepped recess therein formed with curved and plain bottom portions and confronting the said movable jaw, a substantially wedge-shaped lug centrally positioned upon the plain side of said body portion forwardly of said recess, the said lug projecting above said plain bottom portion of the recess and having a curved outer face and a transverse perforation therethrough, a jaw plate substantially conforming in shape to the said recess and pivoted to the said lug and having a bottom socket in register therewith when the jaw plate is positioned within the said recess, the said jaw plate adapted to be swung on its pivot completely out of said recess, spaced leaf springs secured within said recess and resiliently engaging beneath the jaw plate when the latter is in gripping position in the recess and shifting means for the said movable jaw.

In testimony whereof I affix my signature in presence of two witnesses.

J. CASPAR WALIGURSKY.
